BATTERY OPERATED TOOTHBRUSH HANDLE

Isadore Leyden, Shrub Oak, N.Y., assignor to Riviera
Appliance Corp., a corporation of New York

Filed Feb. 18, 1963, Ser. No. 73,621

Term of patent 14 years

(Cl. D9—2)

FIG. 4

FIG. 2

FIG. 1

FIG. 3

FIG. 5

FIGURE 1 is a front elevational view of a battery operated toothbrush handle, showing my new design;
FIGURE 2 is a side elevational view thereof;
FIGURE 3 is a rear elevational view thereof;
FIGURE 4 is a top view thereof; and
FIGURE 5 is a bottom view thereof.

The side not shown is the mirror image of the side shown.

I claim:

The ornamental design for a battery operated toothbrush handle, substantially as shown and described.
